BOOK AND MAGAZINE CABINET OR SIMILAR ARTICLE

George E. Coupland, Ardmore, Okla.

Application March 7, 1949, Serial No. 1,259

Term of patent 3½ years

(Cl. D33—2)

To all whom it may concern:

Be it known that I, George E. Coupland, a citizen of the United States, residing in Ardmore, in the county of Carter and State of Oklahoma, have invented a new, original, and ornamental Design for a Book and Magazine Cabinet or Similar Article, of which the following is a specification, reference being had to the accompanying drawing, forming part thereof.

The figure is a perspective view of a book and magazine cabinet or similar article, showing my new design.

The opposite end is similar to that shown, and the rear is plain.

I claim:

The ornamental design for a book and magazine cabinet or similar article, as shown and described.

GEORGE E. COUPLAND.
